SADDLE RACK OR SIMILAR ARTICLE

Richard Joseph Kadison, 1828 Wyoming Ave.,
Forty Fort, Pa.

Filed Apr. 7, 1964, Ser. No. 79,387

Term of patent 7 years

(Cl. D38—1)

FIG. 1

FIG. 4

FIG. 2

FIG. 3

FIG. 1 is a perspective view of a saddle rack embodying my new design;

FIG. 2 is a top enlarged view of said saddle rack;

FIG. 3 is a side elevational view thereof; and

FIG. 4 is a front elevational view thereof.

I claim:

The ornamental design of a saddle rack or similar article, substantially as shown.
